(57) **CLAIM**

I claim the ornamental design for a charging cable box, as shown and described.

DESCRIPTION

FIG. 1 is a perspective view of the charging cable box;
 FIG. 2 is a top side view thereof;
 FIG. 3 is a bottom side view thereof;
 FIG. 4 is a front side view thereof;
 FIG. 5 is a rear side view thereof;
 FIG. 6 is a right side view thereof;
 FIG. 7 is a left side view thereof;
 FIG. 8 is a perspective view thereof with environmental features; and,
 FIG. 9 is a perspective view thereof with environmental features and the lid removed from the base.
 In FIGS. 8 and 9, the broken lines are for the purpose of illustrating environment only that forms no part of the claimed design.
